UNITED STATES PATENT OFFICE.

PETER M. WEGE, OF GRAND RAPIDS, MICHIGAN, ASSIGNOR TO METAL OFFICE FURNITURE COMPANY, OF GRAND RAPIDS, MICHIGAN, A CORPORATION OF MICHIGAN.

FILING-CASE CONSTRUCTION.

Application filed November 12, 1923. Serial No. 674,130.

This invention relates to a filing case construction, designed to be made of sheet metal. The primary object and purpose of this invention is to provide a novel reinforcement in construction of the case whereby the weight and strength of the sheet metal used is greatly reduced with a corresponding reduction in the cost of manufacture of the device, and at the same time the strength of the case as a whole is not materially changed from a practical standpoint or in any way detrimental to the construction in the matter of service.

The invention consists in novel constructions and arrangements of parts whereby the above ends, as well as others not stated at this time, are effectively attained, as will appear as understanding of the invention is had from the following description, taken 20 in connection with the accompanying drawing, in which,

Fig. 1 is a perspective view of the filing case made in accordance with my invention.

Fig. 2 is a fragmentary enlarged vertical 25 section through the front open end of the case prior to the attachment of the reinforcing wire therefor in place.

Fig. 3 is a vertical section lengthwise of the case with the reinforcing wire secured 30 in place and covered so as to not show, and

Fig. 4 is a transverse vertical section through the case looking to the rear end thereof.

Like reference characters refer to like 35 parts in the different figures of the drawing.

In the construction, the body of the case is made from a single plate of sheet metal of thin gage, bent and formed to provide 40 a horizontal top 1, spaced apart depending vertical sides 2, which at their lower edges are turned inwardly toward each other making bottom member 3, the edges of which abut. A plate 4 of sheet metal lies 45 lengthwise of the case and against the bottom sections 3, being spot welded thereto, said plate at its side edges being formed into upwardly extending inverted U-shaped tracks or guides 5 to serve as supports for 50 a drawer which is to be slidably received in the case.

The rear end of the body of the case thus formed is closed by a back 6 of sheet metal having inwardly turned flanges 7 at its 55 edges adapted to be inserted in the open

rear end of the body. Said flanges are spot welded or otherwise permanently connected to the top, sides and bottom of the case body.

At the front ends of the top, sides and bottom members 3 of the body, the metal is turned inwardly at right angles for a short distance, indicated at 8 and then bent to extend outwardly at right angles to the parts 8, as indicated at 9. Over the projecting portions 9 a rectangular loop of wire or rod 10 is placed and brought back against the parts 8, after which the end portions of the parts 9 are turned outwardly around the loop 10, the edges of the parts 9 being brought against the outer sides of the parts 8, completely covering the wire 10 and securing it in place. The outwardly and rearwardly turned portions of said parts 9 are indicated at 11.

A case constructed as described, at its front open end, where a drawer is to be inserted, is strongly reinforced and strengthened and with the additional strength coming from the construction, the metal used in constructing the case may be reduced materially in thickness. This reduces the cost of manufacture and the price that the consumer must pay to a considerable degree as the major portion of the material used consists of the one plate of sheet metal from which the top, bottom and sides of the case body is made. In addition, the open front end of the case presents a good appearance which makes the finished product attractive to the eye. The invention is simple, very practical, and the construction devised is durable and at the same time light in weight. The invention is defined in the appended claims and is to be considered as 90 comprehensive of all modifications and forms of structure coming within the scope of said claims.

I claim:

1. A filing case construction, comprising 100 a case body formed from a single plate of sheet metal and formed with a top, two depending spaced apart sides, and bottom members turned inwardly toward each other from the lower edges of said sides, a plate 105 located against and secured to the upper sides of said bottom members for connecting the same, said plate lying lengthwise of the body and formed with upwardly projecting drawer supporting guides at its 110

sides, a back of sheet metal closing the rear end of the body, said top, sides and bottom members adjacent their front ends being bent inwardly at right angles for a short distance, then outwardly at right angles, a wire loop located over said outwardly extending portions, said portions being bent outwardly and to the rear over the wire loop, substantially as and for the purposes described.

2. A filing case construction comprising a rectangular case having a top, bottom, sides and ends, said top, bottom and sides

and one end being formed integrally from a single piece of sheet metal, said integrally formed end having an opening surrounded by a wire hoop and the metal at each side of the opening being bent around said hoop to enclose and conceal the same and to form a beaded edge therefor, and the end opposite said integrally formed end being made of a separate piece of sheet metal.

In testimony whereof I affix my signature.

PETER M. WEGE.
